UNITED STATES PATENT OFFICE.

CHARLES A. STRAND, OF CHICAGO, ILLINOIS.

TOOL-HOLDER.

1,361,198.

Specification of Letters Patent.

Patented Dec. 7, 1920.

Application filed March 10, 1919. Serial No. 281,709.

To all whom it may concern:

Be it known that I, CHARLES A. STRAND, a citizen of the United States, residing in Chicago, in the county of Cook and State 5 of Illinois, have invented certain new and useful Improvements in Tool-Holders, of which the following is a specification.

This invention relates to that class of tool-holders which are suitable for holding cutting tools in operative position upon lathes or similar machines.

The principal object of the invention is to provide a simple, economical and efficient tool-holder for lathes or similar machines, 15 adapted to enable any desired cutter or tool of a set to be adjusted to and securely held in the desired operative position in an efficient manner; and to enable each of a plurality or set of cutting tools or lathe tools 20 to be used interchangeably, adjusted accurately and with facility to the desired angle or degree of inclination or operative position, and firmly secured and held in such position so as to perform its work in an efficient manner.

Other and further objects of the invention will appear from the following description and claims, and from an examination of the 30 accompanying drawings, which are made a part hereof.

The invention consists in the features, combinations, and construction and arrangement of parts herein described and claimed.

In the accompanying drawings—

35 Figure 1 is a plan view of a tool-holder constructed in accordance with my invention;

Fig. 2 a view in side elevation of the device shown in Fig. 1;

40 Fig. 3, a similar view in side elevation, with parts broken away, and showing the rotative tool-supporting head with its hub in eccentric relation to its rotative split supporting sleeve, and with said head and hub 45 and sleeve adjusted to a different position from that in which said parts appear in Fig. 2;

Fig. 4, a view in transverse vertical section taken on line 4 of Fig. 2, looking in the direction indicated by the arrow;

Fig. 5, a view in vertical section, taken on line 5—5 of Fig. 1, looking in the direction of the arrow;

55 Fig. 6, a detail view in elevation showing the inner or back side of the rotative tool-

supporting head provided with radial slots adapted to engage the rotative or rocking guiding detent or boss for bracing and securely holding the tool-supporting head against rotation with any desired cutting 60 tool in correct operative position;

Fig. 7, a perspective view of the split sleeve with its eccentric opening or socket, for holding the rotative tool-supporting head in any desired adjusted position into 65 which the head is adapted to be moved;

Fig. 8, an end view of the radially slotted or handle-supporting end of the sleeve shown in Fig. 7;

Fig. 9, a detail view in end elevation of a 70 boring-tool clamping and supporting member having a supporting hub adapted to be removably mounted in the eccentric socket of the sleeve shown in Figs. 4, 5 and 7, when the rotative head shown in Fig. 4 is re- 75 moved; and

Fig. 10, a view in side elevation of the device shown in Fig. 9, with a boring tool 80 clamped and held in operative position thereby.

In constructing a tool-holder for lathes or similar machines, in accordance with my invention I provide a rotative tool-supporting head 1, which is, by preference, of approximately circular form, and is provided with a hub 2, which may be made in one integral piece with the head. The hub shown in the drawing is hollowed out so as to provide an axial opening or socket 3 for admitting the stem 4 of a spring-pressed angular adjustable handle or lever 5 for rotating a split supporting sleeve 6 having an eccentric end opening or socket 7 adapted to admit and engage the periphery of the hub 2 of the tool-supporting head 1. The sleeve 6 has a segmental peripheral groove 8 cut through the peripheral wall of the sleeve at the inner extremity of the eccentric socket or opening and communicating with the latter; and a longitudinal peripheral groove 9 is cut through the entire peripheral wall portion of the sleeve from said circumferential groove 8 to the open end or longitudinally split end of the flexible sleeve. The portion of the sleeve between the peripheral groove 8 and the open or longitudinally slotted or split extremity of the sleeve which encircles the hub 2 when the latter is in operative position in the sleeve, is thus flexible and adapted to be clamped into rigid tightly 105 110

fitting engagement with the hub 2, or with any similar hub of any tool-supporting head or clamping device which may be used in connection with the split sleeve when the head 1 is removed to permit such use of another device. The sleeve has an un-severed peripheral portion 10 which connects the parts of the sleeve which are located on opposite sides of the circumferential segmental 5 groove 8; and the rigid end of the sleeve has an end wall 11 which is provided with an opening 12 therethrough communicating with the eccentric socket 7, and in which is slidably mounted the stem 4 of the operating lever 5 already mentioned.

A head 13 is mounted upon the inner end of the stem 4, and a compressible spring 14 is interposed between the head 13 and the end wall 11 of the split sleeve and encircles 10 the stem 4 so as to tend to press the stem 4 and handle or lever 5 inward. The split sleeve is provided with a series of radial notches 15 in the end thereof adjacent to the angular or radial handle 5 adapted to permit 15 the handle to be yieldingly held in position to extend into any desired one of said notches, and to be adjusted from one to the other of said notches in any desired order. The split sleeve is thus adapted to be rotated with facility by means of said handle 5. It is obvious, however, that any desired ordinary and well known form of handle or operating lever may be employed as a means for rotating the sleeve, and that the 20 sleeve can be rotated manually without any handle or lever; but the lever is a convenient means for enabling the sleeve to be rotated or adjusted with facility.

The tool-supporting head 1 is provided on 25 one side with a series of radial grooves 16, each adapted to admit and removably hold in place a cutting tool. Each of the grooves 16 has an overhanging lip or flange 17 at its outer margin adapted to overlap the adjacent edge of the tool to be inserted in such groove, so as to hold the tool firmly and securely in place in the groove; and a set screw 18 is provided for each groove 16 and mounted in threaded engagement with the 30 rotative tool-supporting head 1 and in position to engage and securely hold in position any tool mounted in such groove.

The head 1 is shown in the drawings provided with a cutting-off tool 19 removably 35 mounted in one groove; an ordinary cutter, such as is commonly known as a diamond point 20 in another groove; a right-hand cutter 21, in another groove, and a left-hand cutter 22 in another groove. It is obvious, 40 however, that the cutters may be of any desired form; and that any desired number of heads 1, with any desired number of cutters of various forms mounted therein, may be used interchangably, with the same split 45 sleeve 6.

An adjustable clamp 23 is provided, which comprises in its construction a main body or standard which forms a lower rigid clamping jaw 24 and has an upper flexible or relatively movable clamping jaw 25 provided with an opening or socket 26 between said clamping jaws adapted to admit and securely hold the split sleeve 6 between said clamping jaws. The upper or flexible clamping jaw is, by preference made in one integral piece with the main body portion or lower rigid upwardly projecting clamping jaw 24 and projects over the latter, said jaw portions being provided with a horizontal notch 27 therebetween which communicates with the circular opening or socket 26, and is adapted to permit the desired relative movement of the upper or movable clamping jaw with respect to the lower or rigid jaw to enable the jaws to be 50 clamped into rigid securing engagement with the split sleeve 6, and to clamp the flexible walls of the split sleeve 6 into snugly fitting rigid engagement with the journal or hub portion 2 of the tool supporting head 50 1, or any similar journal or hub mounted in position to extend into the eccentric opening or socket 7 of said sleeve, and to permit the releasing of the sleeve so as to enable it to be turned or rotated to any desired extent 55 in its circular socket between the jaws and with respect to the journal or hub to be supported by the sleeve. An upright clamping screw 28 extends vertically through the jaws 24 and 25 which are provided with suitable 60 vertical openings for receiving it; and the lower end of the said clamping screw is, by preference, mounted in threaded engagement with a flanged guide 29 which extends beneath and in engagement—preferably 65 clamping engagement—with the bottom face of the clamp 23. The slide guide 29 has side flanges 30 which are adapted to fit into similarly shaped grooved portions of the bed of a lathe, or of a carriage or sliding 70 rest on a lathe, or other suitable support.

The guide 29 thus being mounted in sliding engagement with a suitably grooved support, such, for instance, as the tool-carriage of a lathe, it will be readily seen that the 75 upright clamping screw or bolt 28 is adapted to form a pivot upon which the clamp 23 may be rotated or turned in a horizontal plane or in a plane perpendicular to the axis of the clamping screw, in whatever position 80 the latter may be supported. It should be noted that the flexible split sleeve 6 has an annular circumferential groove 31 in its periphery, adapted to admit and engage the clamping screw 28, which is thus enabled to 85 serve to hold the sleeve in place in its circular socket or space between the clamping jaws, and prevent the sleeve from being moved endwise out of its proper position, 90 while permitting the sleeve to be rotated in 95

either direction as desired to any desired adjusted position, when the clamping jaws are in releasing position, and to be securely clamped in any desired adjusted position by 5 means of the clamping jaws and clamping screw mechanism above described.

The clamp 23 is provided with a base plate or horizontal extension 32 having a segmental slot 33 therein; and a clamping screw 10 34 is mounted in position to extend through said slot and into clamping engagement with the slotted portion of the base plate, so as to rigidly secure and hold the base plate and the clamp or main body of the tool support 15 as a whole in any desired position into which it is adapted to be adjusted or turned upon its vertical pivot formed by the main clamping screw 28. The clamping screw 34 is, by preference anchored or mounted in 20 threaded engagement with the flanged sliding guide 29, in position to project upward through and into slidable clamping engagement with the curved slot 33—the screw 34 being, of course provided with a head or 25 laterally projecting flange portion 35 adapted to engage the slotted base-plate, to hold it clamped in rigid operative position, in any desired adjusted position.

In order to provide simple and efficient 30 means for permitting the rotative tool-supporting head 1 to be rotated to any desired adjusted position, so as to present any desired one of a plurality or set of cutting tools in proper operative position or in position to engage the work or material to be operated upon, and for securely bracing and holding the head and tool in rigid operative position, when so adjusted, and, in that connection, to enable the tool to be tilted to the 35 desired incline, or to horizontal position, or raised or lowered with respect to the center of the chuck or with respect to the work or material to be operated upon, the rotative tool-supporting head 1 is provided with a 40 series of radial slots 36 in its inner or back face, or in position to face toward the clamp 23 and sleeve 6 when the journal or hub 2 of the rotative head is in position in the eccentric socket 7 of the said sleeve; and a 45 detent 37 is mounted in the clamp 23, and by 50 preference, in the upper jaw portion 25 already described, and in position to extend into and in sliding engagement with any desired radial slot 36 in said head 1. The 55 detent is, by preference, in the form of a rocking or rotative pin having an elongated projecting end portion 38 which projects endwise beyond the adjacent outer surface of the clamp or supporting member in which 60 the detent is rockingly or rotatively mounted, and into position to extend into snugly fitting but slidable engagement with any desired slot 36 in the head 1. The detent may be provided with a circumferential peripheral slot 39, into which a set screw or re-

taining screw 40 extends, so as to permit the partial rotation of the detent, so that the latter will conform to the position and degree of inclination or vertical position—as the case may be—of the slot 36 engaged by 70 the detent, when the tool-supporting head 1 is in the desired adjusted position to support the particular tool which is to be used, in the proper operative position.

In order to provide means for enabling 75 another form of tool, such as a boring tool 41 to be mounted and supported in operative position and used in connection with the tool-supporting mechanism above described, when the head 1 is removed to permit the 80 use of such other form of tool, I provide a tool-holder or clamp, a very desirable form of which is shown in Figs. 9 and 10, and which comprises in its construction a main body 42 having a lower rigid clamping jaw 85 43, and upper rigid flange, or jaw 44, and a laterally projecting journal or hub 45 of the same form and dimensions as the journal or hub 2 already described. A movable clamping member 46 is interposed between 90 the upper and lower projecting members or jaws 43 and 44; and one or more set screws or clamping screws 47 are mounted in threaded engagement with the top jaw or flange 44 and in such position that the inner ends 95 of said screws engage the movable clamping member 46, so as to hold the latter in clamping engagement with any tool, such, for instance, as the boring tool 41, which may be mounted between the lower jaw 43 100 and said movable clamping member 46. When the tool-supporting member 42 is to be used, the head 1 is removed from the sleeve 6, and the journal 45 is inserted in the eccentric socket or opening 7 in said sleeve; 105 in place of the hub 2, and the sleeve 6 is clamped into rigid engagement with the hub 45, in the manner already described with reference to the hub or journal 2 of the head 1. The tool holder 42 is provided 110 with a slot 48, which, like the slots 36 in the head 1, is elongated and adapted to admit and slidably engage the detent 37 already described. The tool holder 42 is thus adapted to be adjusted and supported in any desired adjusted position, by means of the tool-holder mechanism shown in Figs. 1 to 8 inclusive.

The handle or lever 48, for operating the clamping screw 28 is removably inserted in 120 any desired suitable lateral opening 49 in said clamping screw, so that, in case the handle happens to reach a position where it would be in the way, when the clamping screw is properly tightened, the handle can 125 be readily removed.

With the four sets of radial slots 36 in the head 1, so disposed that either groove or slot 36 may be adjusted into position to engage the rocking detent 37, the projecting 130

end 38 of which is adapted to extend into any slot 36 which may be brought into position to admit and be engaged by such projecting detent member 38, it is plain that the head 5 1 may be adjusted with facility and with great accuracy so as to rigidly hold the desired tool in operative position with its cutting edge in just the correct position as to height and degree of inclination; and 10 that the clamping and head-supporting member 23, with the head adjustable thereon, is adapted to be adjusted in a horizontal plane with respect to the flanged guide 39, and with respect to the bed of the lathe, or 15 any carriage or support on which the clamp 23 is to be mounted. And the clamping screw 38 serves both as a pivot and a clamping means.

I claim:

20 1. In a tool-holder of the class described, the combination of a clamp having relatively movable clamping jaws, a rotative flexible sleeve mounted between said clamping jaws, said sleeve having an eccentric opening 25 therein, an adjustable rotative tool-supporting head having a journal adapted to extend into said eccentric opening in said sleeve, means for securing a plurality of cutting tools upon said head, means for securing the jaws in clamping engagement with said sleeve, and means for securing the clamp to 30 a support.

2. In a tool-holder of the class described, the combination of a clamp having relatively movable clamping jaws, a rotative flexible sleeve mounted between said jaws, said sleeve having an eccentric opening therein, an adjustable tool-supporting head having a journal rotatively mounted in the 35 eccentric opening in said sleeve, means for securing a plurality of cutting tools upon said head, a detent upon said clamp and in engagement with the adjustable tool-supporting head, said detent being in eccentric relation to the tool-supporting head, a clamping screw in operative engagement with the clamping jaws, for operating the same, and means for securing the clamp to a suitable support.

50 3. In a tool-holder of the class described, the combination of a clamp having relatively movable clamping jaws, a rotative flexible sleeve mounted between said jaws, said sleeve having an eccentric opening 55 therein, an adjustable rotative tool-supporting head having a journal rotatively mounted in the eccentric opening in said sleeve, a detent upon said clamp and in engagement with the adjustable tool-supporting head, a clamping screw in operative engagement with the clamping jaws and adapted to secure the clamping jaw mechanism in clamping engagement with said sleeve, a guide secured to the bottom of said 60 clamp, and means for securing the clamp in 65 clamp, and means for securing the clamp in

different adjusted positions with respect to said guide.

4. In a tool-holder of the class described, the combination of a clamp having relatively movable clamping jaws, a rotative flexible sleeve mounted between said jaws and provided with an eccentric opening in said sleeve, an adjustable rotative tool-supporting head having a journal rotatively mounted in the eccentric opening in said sleeve, a flanged guide in engagement with the bottom of said clamp, and a clamping screw in threaded engagement with said guide and in operative engagement with the clamping jaw mechanism, for opening and closing the latter.

5. In a tool-holder of the class described, the combination of a clamp having relatively movable clamping jaws, a rotative flexible sleeve mounted between said jaws, said sleeve having an eccentric opening therein, an adjustable rotative tool-supporting head having a journal rotatively mounted in the eccentric opening in said sleeve, said head having radial notches adjacent to the clamp, a detent upon said clamp and in eccentric relation to said journal, and adapted to engage any desired radial notch in said head, a clamping screw in operative engagement with the clamping jaws, and means for securing the clamp upon a suitable support.

6. In a tool-holder of the class described, the combination of a clamp having relatively movable clamping jaws, a rotative flexible sleeve mounted between said jaws, said sleeve having an eccentric opening therein, an adjustable rotative tool-supporting head having a journal rotatively mounted in the eccentric opening in said sleeve, said head having radial notches adjacent to the clamp, a detent upon the clamp and adapted to engage any desired radial notch in said adjustable head, a flanged guide in engagement with the bottom of said clamp, and a clamping screw in threaded engagement with said guide and in operative engagement with the clamping jaw mechanism, for operating the latter.

7. In a tool-holder of the class described, the combination of a clamp having relatively movable clamping jaws, a rotative flexible sleeve mounted between said jaws, said sleeve having an eccentric opening therein, an adjustable rotative tool-supporting head having a journal rotatively mounted in the eccentric opening in said sleeve, a flanged guide in engagement with the bottom of said clamp, a clamping screw in threaded engagement with said guide and in operative engagement with the clamping jaw mechanism, and means for securing the clamping jaw in different adjusted positions with respect to said guide, successively.

8. In a tool-holder of the class described, the combination of a clamp having relatively

movable clamping jaws, a rotative flexible sleeve mounted between said jaws, said sleeve having an eccentric opening therein, an adjustable rotative tool-supporting head having 5 a journal rotatively mounted in the eccentric opening in said sleeve, said head having a plurality of notches adjacent to the clamp, a detent upon the clamp and in eccentric relation to the journal and adapted to engage 10 any desired notch in said head, to prevent the rotation of the head when such detent is in engagement with a notch, a flanged guide in engagement with the bottom of said clamp, a clamping screw in threaded engagement

with said guide and extending through said 15 clamp, a base plate upon said clamp and provided with a segmental slot, and a clamping screw in threaded engagement with said guide and extending through the slotted portion of said base plate, for securing the clamp in any desired adjusted position with respect to said guide. 20
